Attorney:

UNITED STATES PATENT OFFICE.

JOHN SKIDMORE, OF CHICAGO, ILLINOIS.

PORTABLE WINDOW-SCAFFOLD.

SPECIFICATION forming part of Letters Patent No. 224,110, dated February 3, 1880.

Application filed September 22, 1879.

To all whom it may concern:

Be it known that I, JOHN SKIDMORE, of the city of Chicago, in the county of Cook and State of Illinois, have invented a new and Improved Portable and Adjustable Balcony for Window-Cleaning Purposes; and I hereby declare the following to be a full, clear, and exact description thereof, reference being had to the accompanying drawing, representing a 10 perspective view of my apparatus as attached to a window-casing.

My invention relates to a device attachable to the outside of window-casings for the convenience and security of a person cleaning the 15 panes; and it consists, first, in the construction of the guard or rail which I employ; and, secondly, in such a guard in combination with my platform, all as hereinafter more fully set forth.

20 My guard is constructed as follows: A A are two bars, each having a socket, *p*, formed upon it at one end, through which a rail, *B*, is passed. A pin, *q*, projects from each bar laterally and outwardly near its opposite end, and 25 a brace, *C*, extends from a point near each socket obliquely downward, backward, and slightly outward. Set-screws *r* permit the clamping of the rail *B* within the sockets.

To adjust the guard a hole is bored in each 30 side of the casing *D* at a suitable height above the sill and outside the sash, whereby the raising and lowering of the same shall not be interfered with by the device. One of the set-screws is tightened and the pin *q* at that end 35 inserted into the proper hole. The other bar is then slid sidewise along the rail until the pin projecting from it enters the opposite hole, when the second set-screw is likewise tightened. The length of the braces *C* should be 40 such that their lower ends will rest against the outside of the casing when the bars *A* are horizontal. It is well, also, to provide them with feet by bending their lower ends, as indicated in the drawing.

45 In order to have my apparatus as light and as strong as possible, I prefer to construct the bars *A* and the rail *B* of iron tubing, and I recommend one-inch gas-pipe for the purpose. They may, however, be made solid, and any 50 other suitable material may be used instead.

It will be seen that the construction of my

guard is one calculated to give the highest possible degree of firmness. Once in position it is incapable of becoming undesignedly detached, and all outward pressure is resisted 55 by the pins *q* and all downward pressure by the braces *C*.

One of the most important features of this guard is, that it is attached to the casing wholly outside the sash, and thus does not interfere with the raising and lowering of the same in the least.

For still greater safety and convenience, especially where the window-ledge is narrow, I add the platform *E*, suspended to the rail *B* by two bars, *s*, which hook at their upper ends over the said rail, as shown, or are otherwise attached to the same, and at their lower ends are hinged to the outer edge of the platform. To prevent this platform from slipping outward I attach 70 two slotted metal plates, *t*, to its inner edge and hook them upon studs *u* in the window-sill. Ordinarily I form these metal plates by continuing the iron strips to which the bars *s* are hinged entirely across the under side of 75 the platform and beyond the inner edge. This has the additional advantage of strengthening the platform.

It may be proper to suggest that while, on the one hand, my guard may be used without 80 the platform, the latter, on the other hand, may be used without the guard. This, however, involves a very obvious modification in the matter of attaching the bars *s*, which must, in this case, be inclined inward and connected 85 in some suitable manner to the window-casing.

My apparatus, with or without the platform, is well adapted for a fire-escape, owing to the ability of the rail *B* to sustain a heavy weight and the safety it affords to persons climbing 90 out at windows. For this reason it may, when not in use for its ordinary purpose, be left attached to a window at some easily accessible point, with a rope conveniently at hand, to be attached to the rail in case of emergency, and 95 thus afford means of descent to the ground without contact with the wall of the building.

What I claim as new, and desire to secure by Letters Patent, is—

1. The combination of the bars *A*, pins *q*, 100 projecting from the same, as shown, whereby they are adapted to enter holes in the window-

casing, braces C, sockets p, rail B, and set-screws r, the whole being constructed and arranged to operate substantially as described.

2. In combination with a guard consisting 5 of a rail sustained in position before a window by means of bars projecting outward from the casing, as set forth, the platform E, resting at its inner edge upon the window-sill, and secured thereto and sustained at its outer edge by 10 bars s, hinged thereto at one end and connecting at their other ends to the said rail, substantially as described.

3. The portable and adjustable balcony for window-washing purposes, comprising the

bars A, pins q, projecting from the same, as 15 shown, whereby they are adapted to enter holes in the casing, braces C, sockets p, rail B, set-screws r, platform E, bars s, hinged to the outer edge of the said platform and hooking over the said rail, and slotted plates t, 20 projecting from the inner edge of the said platform and adapted to catch upon studs in the window-sill, substantially as described.

JOHN SKIDMORE.

In presence of—

P. C. DYRENFORTH,
EDWARD D. WINSLOW.
